UNITED STATES PATENT OFFICE.

JEAN KAUFMANN, OF ST. GALL, SWITZERLAND.

DESIGN FOR ORNAMENTAL FABRIC.

SPECIFICATION forming part of Design No. 35,352, dated November 26, 1901.

Application filed April 4, 1901. Serial No. 54,399. Term of patent 14 years.

To all whom it may concern:

Be it known that I, JEAN KAUFMANN, a citizen of the Republic of Switzerland, residing at St. Gall, Switzerland, have invented and produced a new and original Design for an Ornamental Fabric, of which the following is a specification.

The accompanying drawing represents the design.
The design consists of two embroidered portions *a* and *b*, having ornamental stitches along the lines *c d* and *e f* between them. The general outline of the border or frame consists of convex and concave outlines *h* and *i* in juxtaposition and combined to form an asymmetric frame of the general type of ornamentation known as rococo design. The interior has a cut-away portion *g*, also

of asymmetric outline, formed by concave and convex curves, as shown, not conforming to the exterior edge of the border and provided with stitches substantially radial to the line of cut. The space intermediate the inner and outer edge of the border is ornamented with sprays of flowers, as shown. 20 25

What I claim is—

The design for an ornamental fabric, substantially as herein shown and described.

In testimony whereof I have signed my name to this specification in the presence of 30 two subscribing witnesses.

JEAN KAUFMANN.
